(No Model.)

J. W. DELMEGE.
TELEGRAPH SOUNDER.

No. 319,201.

Patented June 2, 1885.

UNITED STATES PATENT OFFICE.

JOHN W. DELMEGE, OF NORTH BILLERICA, MASSACHUSETTS.

TELEGRAPH-SOUNDER.

SPECIFICATION forming part of Letters Patent No. 319,201, dated June 2, 1885.

Application filed December 17, 1884. (No model.)

To all whom it may concern:

Be it known that I, JOHN W. DELMEGE, a citizen of the United States, residing at North Billerica, in the county of Middlesex and State 5 of Massachusetts, have invented certain Improvements in Telegraph-Sounders, of which the following is a full, clear, and exact description, reference being had to the accompanying drawings, making part of this specification, in which—

Figure 1 is a perspective view of a telegraph-sounder constructed in accordance with my invention. Fig. 2 is a vertical section through the center of the same.

15 My invention has for its object to simplify the construction of telegraphic sounding-instruments, and enable them to produce a louder and clearer sound without unnecessary vibration or ringing, and with much less battery-power than heretofore; and my invention consists in the combination, with a pair of electro-magnets and a metallic sounding-frame having at its upper and lower ends screws or anvils, of a sounding post or bar carrying the 25 armature of the electro-magnets and sliding in guides or bearings in the said sounding-frame, and operated longitudinally in one direction by the said magnets, and in the opposite direction by a spring, whereby its upper 30 and lower ends are alternately brought into contact with the upper and lower anvils to produce the signals, as hereinafter set forth.

In the said drawings, A represents the base-board of my telegraph-sounder, within which 35 is inserted the metal plate b, to which are secured at two opposite ends the two electro-magnets B B, which are connected in the usual manner with the battery and the main line by wires entering the binding-posts c c.

40 D represents the metallic sounding-frame, of the form shown, which is placed centrally between the two electro-magnets B B, and is secured at its lower ends, by means of screws e, to the plate b, which forms the bottom of the 45 frame.

G is the sounding post or bar, which slides freely in guides or bearings 5 in the transverse bars d of the frame D, the upper end of the post G being turned down, leaving a shoulder, 50 f, on which rests the armature H, which is firmly secured to the sounding-post beneath the upper bar, d, of the frame D.

g is a screw, which passes up through the plate b in line with the axis of the sounding-post G, and constitutes the lower anvil, against 55 which the lower end of the sounding-post G is caused to strike when the electro-magnets are charged, and h is a thumb-screw, which passes down through the top of the frame D immediately in line with the post G, and forms the 60 upper anvil, against which the upper extremity of the said post is caused to strike when the armature H is released by the discharging of the electro-magnets by means of a lever, i, pivoted to the frame D, the inner end of this 65 lever entering a recess in the post G, and its outer end being connected with a spring, k, the tension of which is regulated by turning the nut l on the screw m, to which the spring is attached. If desired, the lever i may be 70 dispensed with and the spring k connected directly with the sounding-post without the employment of any intermediate mechanism. The screw h is provided above the top of the frame D with a check-nut, n, to confine it 75 tightly when adjusted, and by turning this screw h the sounding-post G can be adjusted to vary the length of its stroke, whereby more or less sound, or a variation in the tone, is produced, as the post, by the alternate action of 80 the electro-magnets B B and spring k, is moved up and down in its bearings 5 in the frame to bring its opposite ends alternately into contact with the anvils h g. The armature H is adjusted nearer to or farther from the electro-magnets, as may be found desirable, by turning the lower screw or anvil, g, which thus 85 limits the downward movement of the sounding-post, which carries the armature. The sounding-post and armature have a free and 90 easy movement with the action of the key, and are not liable to stick or bind, as frequently occurs with the lever of an ordinary sounding-instrument if the fulcrum-screws are unduly tightened through the carelessness or ignorance of the operator. The metallic sounding-frame D is of such shape and size as to 95 produce the signals in a loud, clear, and firm tone when the post G strikes the anvils, and by arranging this frame D between the two 100 electro-magnets the instrument can be made exceedingly compact, and is, moreover, of very simple construction and not liable to get out of order.

One of the principal advantages of my improved construction is, that a louder and clearer sound can be produced with a single cell of battery than can be produced with two cells 5 of battery, where the ordinary lever-sounder in common use is employed, as there is no leverage to overcome, and much less force is required to bring the sounding-post into contact with the anvils with sufficient force to 10 produce the required volume of sound than is required to operate the sounder-lever of an ordinary instrument, a material saving in battery-power being thus effected, which is a very important consideration. Furthermore, less 15 resistance is produced on the transmitting-key on account of the ease with which my improved sounder is operated.

I do not claim, broadly, a sounding post or bar adapted to move vertically between two 20 anvils, as I am aware that such construction is not new; but

What I claim as my invention, and desire to secure by Letters Patent, is—

In a telegraph-sounder, the combination, 25 with the electro-magnets B B and the sounding-frame centrally arranged between the said magnets, of the slotted sounding post or bar sliding in guides or bearings in the sounding-frame, a shoulder on the sounding-post, the armature H, resting on the shoulder, the adjustable anvils h g, a lever engaging the post, and a tension-spring, k, all operating substantially as and for the purpose described.

Witness my hand this 15th day of December, A D. 1884.

JOHN W. DELMEGE.

In presence of—

P. E. TESCHEMACHER,
W. J. CAMBRIDGE.
